UNITED STATES PATENT OFFICE.

JOHN H. GILES AND DONALD M. GILES, OF AMSTERDAM, NEW YORK, ASSIGNEES TO JOHN H. GILES DYEING MACHINE COMPANY, OF PORTLAND, MAINE, A CORPORATION OF MAINE.

DYEING-MACHINE.

1,114,464.

Specification of Letters Patent. Patented Oct. 20, 1914.

Application filed December 29, 1913. Serial No. 809,177.

To all whom it may concern:

Be it known that we, JOHN H. GILES and DONALD M. GILES, citizens of the United States, residing at Amsterdam, in the county 5 of Montgomery and State of New York, have invented new and useful Improvements in Dyeing-Machines, of which the following is a specification.

This invention relates to machines for 10 the dyeing of yarns and the like and consists in a new and durable construction and improved arrangement whereby danger from the corroding action of the dye liquor on the parts is avoided, in this respect over- 15 coming an objectionable and highly detrimental defect heretofore present in machines of this character. To this end we have devised means for rotating the supporting sticks from which the springs heretofore 20 commonly employed are eliminated, thereby reducing the liability of interrupting the operation and causing improper dyeing of the yarn by reason of broken springs. Such 25 springs are preferably made of steel or bronze, and when subjected to the action of certain dyes, such as black sulfur dye and acid colors, the corrosion is so great that it is necessary to replace them very often 30 to insure against their breaking, and the consequent production of imperfectly dyed 35 yarn.

Important features of our improved machine consist in an escapement dog associated with the advancing mechanism for 40 rotating the sticks, which support the skeins of yarn, whereby the sticks may periodically be rotated and held, without the use of springs which require constant renewing as aforesaid; an improved adjusting mechanism for the inner series of supporting sticks operative simultaneously to adjust all the inner stick bearings with relation to the outer series of sticks, this mechanism being 45 of a character wherein removable securing parts are not required and adapted to be actuated by a removable wrench thereby to afford a cool operating handle for the operator; an improved trip device for changing 50 of the position of the yarn on the sticks, adapted to permit moving of the sticks in the reverse direction without damage to the parts; an improved form of supporting stick more easily cleaned and having no tendency 55 to absorb the dye and improved bearings for the sticks giving an increased length of

stick available for supporting the work thereby enabling a larger load to be dyed at one time in the machine.

These and numerous other features of our invention which contribute to the convenience and efficiency of our improved machine are shown in the accompanying drawings wherein a desirable embodiment of our invention is illustrated and wherein the reference characters of this description are applied to like parts in the several views.

In the drawings Figure 1 is a vertical cross-sectional view of a machine constructed to embody the features of our invention; Fig. 2 is a detail view showing in elevation 60 our improved escapement arrangement employed in rotating the sticks. Figs. 3 and 4 are detail views showing the opposite bearings for the outer sticks, Fig. 3 being a central sectional view taken on line 3—3 of 65 Fig. 2 and Fig. 4 being partially in section on the same plane. Fig. 5 is a vertical longitudinal sectional view of the machine of Fig. 1. Fig. 6 is a detail sectional view of the thermal regulator employed; Figs. 7 and 8 are views taken respectively in side 70 and end elevation showing our improved trip. Fig. 9 is a detail view of the holding parts for the inner sticks; Fig. 10 is a sectional view of an improved form of supporting stick; Fig. 11 is a vertical longitudinal 75 sectional view of our improved double stick machine showing the means for adjusting the inner sticks. Fig. 12 is a detail sectional view of our improved double 80 socket bearing; Fig. 13 is a view in end elevation of the described machine showing the driving gear mechanism in section; Fig. 14 is a partial detail view in left side elevation showing the inner stick adjusting arrangement. Fig. 15 is a view showing the 85 agitating mechanism in rear elevation. Fig. 16 is a detail view showing the rest spring for the rail gate. Fig. 17 is an enlarged detail view in section, on line x x of Fig. 18, showing our improved form of steam 90 distributing pipe. Fig. 18 is a view in elevation and partial section showing the same and our improved manner of dividing the steam. Figs. 19 and 20 are fragmentary 95 views illustrating a modified stick holding arrangement in side elevation and in plan, and Fig. 21 is a view partially in elevation and partially in section showing a modified protected stick.

Referring to the drawings the machine comprises the dye-tub or vat T containing the dye liquor substantially to the level shown. In bearings 2—2 at the ends of the tub is journaled a central supporting shaft 3, having fixed thereon within the tub the spiders S, the spokes 5 thereof supporting the outer and inner bearing rings 6 and 7 oppositely arranged and provided with bearings for the outer and inner series of longitudinally arranged yarn supporting sticks 10 and 11 respectively. The skeins of yarn to be dyed are suspended between the sticks of the outer and inner series or double reels in the manner indicated in dotted lines Fig. 1 and upon revolving the rotary carrier formed by the spiders and sticks the yarn is carried downwardly through the dye liquor. As illustrated in Figs. 5 and 13 the supporting shaft 3 is rotated by the engagement of a driving worm 12 on a drive shaft 13, with a worm gear 14 secured on the end of shaft 3 and with the shaft the spiders and sticks are revolved to immerse the yarn as described.

Upon each revolution of the sticks it is desirable that each shall be rotated sufficiently and independently on its own axis to change the position of the yarn thereon so that a different portion of the skein will be in contact with the stick during each revolution. This is necessary as the portion of the yarn in engagement with the stick is protected from the dye, so that to continue the engagement of the same portion of the skein with the stick for a length of time will prevent the uniform absorption of the dye by that portion. Therefore to change the position of the yarn it has been customary to turn the outer sticks at each revolution of the reel, but the means heretofore employed for that purpose have required the use of springs in their operation, which, under the peculiar conditions present, are particularly undesirable and defective. The reasons therefor are that the springs, which for purposes of strength and resiliency are of steel, or bronze, are subjected to the action of the dye liquor with the result that they are soon ruined by corrosion. Frequent renewing of the springs is therefore required causing trouble and expense.

Our improved device for advancing the yarn on the sticks operates without the use of springs and consists, as best shown in Figs. 2 and 3, of a socket-bearing 16 journaled in the outer ring or segment 6. On the outwardly projecting portion 18 of the bearing is mounted the star wheel 19 secured by pin 20. The inner end of the bearing is formed with a squared socket 22 to receive the squared end 23 of the yarn sticks 10 and also has integrally formed therewith the ratchet flange 24 having ratchet teeth 25. The rotatable bearing 16 is secured from

endwise movement by the flange 24 and by projections 26 on the star wheel engaging an annular bearing flange 28 of the ring 6. The arrangement is such that the star wheel is engaged by a suitable trip t on each revolution of the sticks to effect a quarter turn of the bearing and stick so that the position of the yarn is shifted. To retain the stick in its advanced position when rotated by the star wheel, a dog 30 is hung on a pivot pin 31 secured on the ring 6 so that the opposite detents 33—34 thereof alternately will engage the ratchet teeth 25. The inclined surfaces of the ratchet teeth will rock the dog on the advance rotation of the bearing, alternately throwing the detents 33—34 out of engagement, so that the ratchet is permitted to turn, but the constant engagement of the teeth prevents all danger of return movement of the stick in any position thus insuring positive action and overcoming any tendency of the stick returning under the reaction of the yarn owing to its stretched condition with consequent danger of stick marks. The dog may desirably be of the form shown so as to be weighted, so as to insure engagement of one or the other detent even when teeth or detents wear.

The securing pin 20 for the star wheel 19 is desirably made of a soft metal such as copper or it may be weakened so as to form a safety shearing connection, for rotating the stick, to avoid breaking of the mechanism and to protect the ratchet teeth under excessive strain should the yarn become twisted around the stick.

As shown best in Fig. 4 the bearings for the sticks in the opposite ring are simply circular apertures to receive the elongated ferrules or spindles 36 on the stick ends. To place the sticks in the machine the ferrules are inserted into the apertures far enough to permit the squared ends 23 at the opposite side (Fig. 3) to be inserted in the sockets 22 of the bearing 16. An annular retaining or backing rail 38 is secured on the end of the machine adjacent to the apertured ring 6 in position to retain the sticks in the squared socket at the opposite side by engagement with the end of the ferrules. Immediately within the front cover 40 of the top 41 of the machine a portion 38' of the retaining ring is hinged at 42 to allow for its being swung out of engaging position with the ferrules thus permitting the required longitudinal movement of the sticks during their insertion and removal. The bearings as described are particularly desirable as they give an increased length of stick available for supporting the yarn thereby increasing the capacity of the machine. Moreover the arrangement is convenient and facilitates the placing of the sticks.

Supported upon the spiders S are shown

the usual guard rings 44-44' arranged to keep the yarn from the bearings of the respective sticks 10 and 11. As shown the rings are in close proximity to the sticks whereby they best perform their function.

5 In Fig. 11 there are illustrated the features of our invention embodied in a double stick machine wherein three supporting spiders S are provided each carrying outer and inner bearing rings 6 and 7. In this construction the sticks 10 of each half are arranged in longitudinal alinement and double socket bearings 45 of peculiar construction are journaled in the central ring 6 whereby the parallel sticks are rotated together. The sticks at their outer ends are fitted to apertured rings and are retained in position by the arrangement described and shown in Fig. 4.

20 In Fig. 12 our improved double socket bearing is shown in detail and has at each side a squared socket 22 for the ends of the opposite sticks. Upon the bearing is formed the ratchet flange 16 to coöperate with an escapement dog similar to the arrangement of Fig. 2 and likewise at the opposite side there is arranged the star wheel 19 to coact with a center trip similar to trip t of Fig. 1 and now to be described in connection with Figs. 7 and 8.

Our improved trip is shown pivotally supported on pin 47 in a bracket 48 secured on the under side of the top 41 of the machine. It includes the depending trip arm 50 having adjustably supported at its end an anti-friction roller 51 positioned to engage the fingers of the star wheels 19 for the purpose of causing their rotation. The sticks are revolved in the direction shown by arrow in Fig. 1 and the depending trip arm 50 has a lateral arm 54 carrying an adjusting screw 55 to engage a lug 56 on an upwardly extending arm 57 also pivotally supported on pin 47. The arm 57 is held 45 to be normally rigid so that the roller 51 in the path of the revolving star wheels to be engaged thereby, will be held rigid through the engagement of screw 55 and lug 56 to rotate the star wheels a distance 50 determined by the position of the roller up and down in its slot. The depending stop arm 50 is free to swing toward the left away from the arm 57 thereby yielding to permit a reverse revolution of the sticks for unloading the yarn without disturbing the trip device. A counter-balance weight 60 is provided on the arm 50 normally to maintain it in its operative position. Provision is also made adapting our improved trip to 55 yield in a forward direction under excess pressure as may be caused by the resistance offered by the star wheels when yarn is wound around the stick. To that end a spring 65 is connected to the upper 60 end of the arm 57 and to a fixed bracket 66.

An elongated slot is provided in the top for the reverse swing of the arm 57. Supported on parallel rods (67) carried by suitable brackets on the top of the machine may also be arranged the buffer springs 68-68 bearing against a cross piece 69 slidably carried on the rods to be engaged by the arm 57 as best shown in Figs. 1 and 8. The springs 68 thus form a buffer to check the rebound of spring 65. Adjusting nuts 70 are provided in the rods 67 to adjust the initial forward position of the cross-piece and thereby adjust the normal position of the trip. The trip shown is yieldable in both directions, thus automatically accommodating for the reverse movement of the machine without the removal of parts and to protect the parts if the yarn should become tangled on the sticks. A bell 22 has a connection to the arm 57 to give an alarm 85 when the sticks are not rotating as they should.

In Figs. 1, 11 and 14 there is illustrated our improved stick adjusting mechanism operative to adjust the distance between the outer sticks 10 and the inner sticks 11 best to suit the length of skeins on the sticks. For that purpose the inner bearing rings 7 are rotatively supported on the spiders; bearings therefor being provided by the ends 5' of the inner reinforcing ribs of the spokes 5. Suitable clips 75 on the spokes engage the outer edges of the rings to hold them in position. The two inner bearing rings at the center of the double machine shown in Fig. 11 are desirably secured together by bolts or otherwise so that they will turn together thus forming a double bearing ring. On the inner periphery of the bearing rings a rack or toothed segment 76 is provided. Journaled in suitable bearing brackets 78 carried by the spokes 5 is a longitudinally arranged shaft 80 having on its end a worm gear 81 whereby it is turned to shift the bearing rings by the engagement of the pinions 83 thereon with the teeth of the racks 76. A radially arranged actuating shaft 84 is journaled in suitable brackets 78' (Fig. 14) and 85 on the spokes and outer ring 6; upon said actuating shaft is arranged a driving worm 86 in engagement with the worm gear 81. The outer end of the actuating shaft 84 is squared for the engagement of a suitable detachable operating wrench by the operation of which all of the inner bearing rings and sticks will be moved together with relation to the outer yarn sticks. In employing the worm 86 to effect the adjustment of the sticks detachable securing means to retain the parts in adjusted position are not required and the use of the detachable wrench affords a cool handle for the operator.

Referring to Fig. 9, there is shown a desirable form of stick bearing socket well 130

adapted for supporting the inner sticks. The bearing ring 7 is formed with integral socket flanges 88 open at one side to receive the sticks and a retaining cover 90 is pivotally supported on pin 91 adjacent to each socket. The cover normally is held in the position shown by a spring 93 attached to it and to the bearing ring 7. A stop projection 94 is provided on the cover to engage the socket flange when in securing position. The inner sticks 11 are similar in form to the outer sticks shown in Figs. 3 and 4 and to insert them in the machine the ferrules at one end are inserted in suitable apertures 15 in one of the rings 7 and the opposite ring is provided with the socket arrangement just described. The squared end of the stick is pressed against the upper surface of the cover 90 forcing it to yield against the 20 action of the spring 93 to permit the entry of the stick into the socket. The inner sticks are desirably held from rotating so that the tendency of loose ends of yarn to wrap around the stick will be reduced. The 25 sockets 88 and sticks are therefore preferably squared.

The arrangement of the spring 93 is an additional feature of this invention. It consists in an expansion spring device composed 30 of the hooked supporting wires or shanks 95 having the usual hooks or loops for attaching to the cover and to the ring. The inner ends of each shank are formed with a loop 96 encircling the other shank. Surrounding the shanks is the spiral spring 93 having contracted ends to engage the shank loops 96. The spring is thus confined between the loops so that when the shank ends are drawn apart or expanded the spring 93 40 will be compressed. The life of the springs by this arrangement is prolonged for when fully compressed they provide a stop to limit the movement of the covers 90 and therefore can not be subjected to excess 45 strains.

An improved construction for promoting and controlling the circulation of the dye liquor is best shown in Figs. 1, 5 and 18. The dye liquor may be heated by a steam jet 50 introduced through a central feed-in pipe 100 and longitudinally arranged distributing pipe 102. The dye tub T is of curved form and the shaft 3 is supported at one side of the central axis thereof. At the opposite side is arranged a curved partition board 103 with its upper edge slightly below the level of the liquor and having its lower portion arranged, conjointly with an inclined base board 104, to form a contracted 55 opening 105 communicating with the space behind the partition. The entrance to the opening, as shown, desirably may be flared. The steam distributing pipe 102 is arranged immediately behind the opening 105 and has

openings to direct the steam toward said 65 opening, thereby heating the liquor and establishing a desirable circulation of the dye liquid, more evenly to distribute the dye. The circulation so effected will be seen to be in a clockwise direction as indicated 70 by arrows in Fig. 1, the liquor moving to the rear at the bottom of the tub and at the top passing forwardly over the partition 103 and downwardly behind it. The pressure of the steam as it enters the bath will maintain this circulation and in so doing is assisted by the paddle action of the yarn entering 75 the bath.

Absolutely to prevent the steam, under a lowered pressure from rising behind the partition and tending to oppose or reverse the circulation there is provided the check valve 108 hinged at 109. This valve 108 in the event of an upward flow within the passage 80 behind the partition, will close against a stop 110 with the result that steam rising behind the partition will build up a pressure 85 forcing the liquor out through the opening to reestablish the proper circulation.

In Figs. 17 and 18 is shown an improved 90 form of distributing pipe 102 for the admission of the steam to the bath wherein the pipe is formed of sheet metal rolled up into cylindrical form with its edges 115 turned inwardly to provide a longitudinal slot 116. 95 The slot so formed desirably may be of increasing width toward the outer ends of the pipe thereby compensating for the reducing pressure of steam toward the ends and effecting a more even distribution thereof. 100 An adjusting bolt 118 may desirably be provided at the ends of the pipe to adjust the space between the pipe edges.

A further feature contributing to the uniform distribution of the steam consists in 105 providing a central division wall 120 in the pipe coupling 122 extending upwardly a short distance within the feed-in pipe 100. Thereby is accomplished a positive mechanical division of the steam passed to the 110 branches of the distributing pipe 102.

The dye is supplied to the bath from a suitable receptacle 124 through inlet pipe 125 and a longitudinal distributing pipe 126 suitably apertured. A valve 128 is arranged 115 in pipe 126 to regulate the flow of dye. (Fig. 1).

Thoroughly to mix the dye with the liquor as it is admitted to the bath from the distributing pipe 126 there are provided a series of agitating sticks or paddles 130 pivotally hung from a horizontal bearing bar 131 parallel to the pipe 126 (Figs. 1 and 15). These agitators are connected by a link 132 pivotally secured to each and are actuated by a rotating lever 133 fulcrumed in a bracket on the tub. One arm of lever 133 is connected by link 134 to arm 135 of the

end agitator and the other of its arms is connected to an eccentric arm 137 operated by the eccentric 138 on power shaft 13.

In Figs. 5 and 6 is shown our improved method of regulating the temperature of the bath whereby the same may be maintained at the desired temperature best adapted for dyeing. It consists in an automatically controlled regulating valve 140 having the usual 10 valve seat 141 and an operating stem 142. The valve stem is connected by a small link 144 with the stem 146 connected to a suitable spring expansion bellows 147 supported on frame 148. Thereby the valve is operated on 15 the contraction and expansion of the bellows to open and close the valve. The desired movement of the bellows is effected by the action of a suitable expandable fluid contained within the hollow tube 150 extending 20 into the bath and communicating with the interior of the bellows through a pipe 152. The fluid is thus subjected to the temperatures of the bath to be expanded to close the valve when the heat of the bath becomes 25 excessive. An adjustment of the regulation is provided by a counter-balance weight 154 adjustably supported on a bar 155 fulcrumed on a supporting link 157 and connected to the intermediate link 144. As 30 shown the automatically controlled valve 140 is arranged in a branch 100' around a direct valve 158. The branch is provided with valves 159-159 to be opened when automatic control is desired at which time 35 valve 158 will be closed.

Desirable forms of improved yarn stick are shown in Figs. 10 and 21. In Fig. 10 a metallic stick is shown formed of a rolled up, corrugated sheet of metal 160 having its 40 edges turned inwardly and secured to a block 162. In Fig. 21 is shown a modified form in which the metal is coated with a protective covering 163 of non-corrosive material of low heat conducting value. The 45 bearings for the sticks, as shown in Fig. 21 may desirably be formed of special non-corrosive metal by providing the ferrule 36 at one end and the squared shoulder 23 at the opposite end.

50 Our improved stick of the character described will not absorb the colors of the dyes and may easily be washed permitting its use in a dye of different color. Moreover the coating of low heat conducting 55 material will afford a cooler stick for handling.

In Fig. 13 the driving parts are shown to include the usual changeable gear box G whereby the revolving of the sticks may be 60 effected at different speeds and reversed for unloading of the yarn. This reverse is desirably effected at the same speed as the low speed forward. The power is transmitted through the gear box from a driving pulley

166 and clutch 168. As a further feature 65 the driving shaft 13 is provided on its end with a squared portion 169 to be engaged by a wrench handle for manual turning thereof should the power give out. The batch of 70 yarn being dyed may thus be saved from being unevenly dyed and spoiled in an emergency.

A modified form of stick holding device is here illustrated in Figs. 19 and 20. It relates to the bearing for the ferrule end of the 75 sticks and the means for holding them from being longitudinally withdrawn from the socket bearings described at the opposite end. A flat spring 170 having a reinforcing leaf 171 is secured by suitable rivets to 80 the outer side of the ring to bear upon the ends of the stick ferrules 36 whereby they are held in position. As shown at the right in Fig. 19 these holding springs 170 will yield to permit the required lengthwise 85 movement of the stick for insertion and withdrawal from the socket bearing. This arrangement is particularly desirable as the springs operate by a mere pressure on the sticks. To safeguard against lateral stresses 90 which may be excited during the turning of the sticks by the trip *t* a stationary cam 172 may be supported on the tub in position as shown in dotted lines Fig. 20, to prevent 95 longitudinal movement of the sticks at that point.

The location of the thermostat tube as shown at the extreme opposite side of the vat from the point of introducing the steam renders it responsive to the temperature of 10 the bath in a manner likewise having an influence in controlling the proper circulation of the dye liquor. This effect obtained thereby is that upon a cessation of the proper circulation of the liquor (owing to 10 reduced steam pressure or otherwise) the steam as it enters the bath will not be carried to the opposite wall but will rise directly. Therefore the liquor in the vicinity of the tube will cool and will actuate the thermostat to open the controlling valve to re-establish the proper circulation.

Having described our invention, we claim,

1. In a dyeing machine the combination 11 with a vat and yarn stick supporting members revolving into the vat, of means for changing the position of the yarn on the sticks comprising a stick bearing member journaled in the supporting members, a yarn supporting stick carried by said bearing member, a ratchet on the bearing member, a double detent escapement dog arranged whereby its detents alternately engage the ratchet teeth to prevent turning of the bearing in one direction and adapted to permit turning of the bearing in the other or advance direction and means to rotate the bear- 12

ing member in the advance direction to change the position of the yarn on the stick.

2. In a dyeing machine, the combination with a vat and yarn stick supporting members revolving in the vat, of means for changing the position of the yarn on the sticks comprising a stick bearing member journaled in the supporting members, a yarn supporting stick carried by said bearing member, a ratchet on the bearing member, a rocking escapement dog suitably fulcrumed, detents at the opposite ends of the escapement dog adapted alternately to release the ratchet teeth when the bearing is turned in one direction and adapted to prevent turning of the ratchet in the opposite direction, said dog being weighted to effect full engagement of the detents, a star wheel mounted on the bearing member and a trip positioned to be engaged by said star wheel to effect turning of the bearing and changing of the position of the yarn on the stick.

3. In a dyeing machine, the combination with a vat and yarn stick supporting members revolving in the vat, of means for changing the position of the yarn on the sticks comprising a stick bearing member journaled in the supporting members, a yarn supporting stick carried by said bearing member, a ratchet on the bearing member, a rocking escapement dog suitably fulcrumed, detents at the opposite ends of the escapement dog adapted alternately to release the ratchet teeth when the bearing is turned in one direction and adapted to prevent turning of the ratchet in the opposite direction, said dog being weighted to effect full engagement of the detents, a star wheel mounted on the bearing member, a securing pin for the star wheel of relatively soft metal, and a trip positioned to be engaged by said star wheel to effect turning of the bearing and changing of the position of the yarn on the stick.

4. In a dyeing machine, the combination with a dye vat and yarn stick supporting members revolving in the vat, of means for changing the position of the yarn on the sticks comprising a stick bearing member journaled in the supporting members, a ratchet on the bearing member to one side of the supporting member, a star wheel on the bearing member at the other side of the supporting member, means to engage the star wheel to rotate the bearing and means to engage the ratchet to prevent reverse movement of the bearing member, said bearing member being formed with sockets for the sticks on its opposite faces inclosed by the star wheel and ratchets respectively.

5. In a dyeing machine, the combination with a vat and yarn stick supporting members arranged to revolve into the vat, of bearings for the sticks carried by the sup-

porting members the bearings consisting of 65 socket elements on one supporting member and an apertured element on the opposite member, yarn supporting sticks arranged at one end to enter the apertures to permit entry of their opposite ends in the sockets and 70 a guard rail suitably supported to engage the stick spindles to retain the sticks within the sockets during the operation of the machine.

6. In a dyeing machine, the combination 75 with a vat and yarn stick supporting members arranged to revolve into the vat, of bearings for the sticks carried by the supporting members, said bearings consisting of socket elements on one supporting member 80 and an apertured ring on the opposite member, yarn supporting sticks having elongated spindles at one end to enter the apertures to permit entry of their opposite ends in the sockets, a guard rail suitably supported 85 to engage the stick spindles to retain the sticks within the sockets during the operation of the machine and a removable gate portion forming a part of said rail and adapted to permit the entry and removal of 90 the sticks.

7. In a dyeing machine, the combination with a dye vat and yarn stick supporting members arranged to revolve into the vat, of bearings for the sticks carried by the supporting members, said bearings consisting of socket elements on one supporting member and an apertured ring on the opposite member, yarn supporting sticks having elongated spindles at one end to enter the apertures to permit entry of their opposite ends in the sockets and squared portions on said opposite ends of the sticks to enter the sockets, an annular guard rail supported on the vat to engage the stick spindles to retain 1 the sticks within the sockets during the operation of the machine, a hinged gate portion forming a part of the guard rail adapted to be swung into a non-engaging position to permit a longitudinal movement of the sticks for the entry and removal thereof and means to retain the gate in non-engaging position.

8. In a dyeing machine the combination with a vat and yarn stick supporting members revolving in the vat, of means for changing the position of the yarn on the sticks comprising a stick bearing member journaled in the supporting members, a yarn supporting stick carried by said bearing member, a ratchet on the bearing member, a double detent escapement dog arranged whereby its detents alternately engage the ratchet teeth to prevent turning of the bearing in one direction and adapted to permit turning of the bearing in the advance direction, said dog being weighted to effect full engagement of the detents and means

to rotate the bearing member in the advance direction to change the position of the yarn on the stick.

9. A dyeing machine comprising a dye vat, yarn stick supporting members arranged to be revolved into the vat, stick bearing members journaled in one of the supporting members, yarn supporting sticks fitted to the journaled bearing members to rotate therewith, means to prevent rotation of the bearings in one direction and means to effect the rotation of the bearings in the other direction comprising a two part trip arm suitably journaled and having a secured arm and an engaging arm movable independently thereof in one direction upon engagement with the journaled bearings and adapted to abut the secured arm when engaged by the bearings from the other direction and yieldable securing means for said secured arm adapted to hold said arm rigid to effect turning of the sticks under normal conditions and to yield under excessive stresses.

10. A dyeing machine comprising a dye vat, yarn stick supporting members arranged to be revolved into the vat, stick-bearing members journaled in one of the supporting members, yarn supporting sticks fitted to the journaled bearing members to rotate therewith, means to prevent rotation of the bearings in one direction and means to effect the rotation of the bearings in the other direction comprising a two part trip arm suitably

journaled and having a secured arm and 35 an engaging arm movable independently thereof in one direction upon engagement by the bearings, abutting stops carried by the respective arms, an adjusting screw carried by one of the stops, a counterweight 40 on the engaging arm, an adjustable anti-friction roller on the engaging arm, a securing spring connected to the secured arm to hold said arm rigid to effect turning of the sticks, said spring being proportioned to 45 hold the arm rigid under normal operating conditions and to yield under excess pressure and a buffer spring to cushion the rebound of the securing spring.

11. A dyeing machine having in combination with a dye vat and yarn stick supporting members revolving in the vat, of means for changing the position of the yarn on the sticks comprising a rotatable stick bearing member journaled in one of the supporting members, means to rotate the bearing member and said bearing member being arranged on its opposite sides to provide bearings for yarn sticks arranged in axial alinement.

In testimony whereof we have signed our names to this specification in the presence of two subscribing witnesses.

JOHN H. GILES.
DONALD M. GILES.
